UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

FLUID COMPRESSOR.

Application filed September 5, 1925. Serial No. 54,632.

My invention relates to fluid compressors and the general object is to provide improved construction and arrangement for cooling and preventing overheating of the discharge end. My invention is particularly applicable to the type of compressors disclosed in my co-pending application, Serial No. 737,725, filed September 15, 1924, in which I have shown a sleeve valve operated by ring friction and specifically an elastic, yieldable and non-metallic seat inserted in the cylinder head for noiseless sealing engagement with the upper end of the sleeve or liner intake valve, but it is not intended to limit the present invention to such specific embodiment. The discharge valve construction of my invention is of great value regardless of the character of the intake valve construction.

The heat caused by the compression of the fluid has its greatest effect upon the compressor at the discharge end of the cylinder and in the discharge passageway. The surrounding material soon becomes heated and the heat of the head and upper end of the cylinder tends to build up the temperature to a point where cylinder lubrication fails and the compressor can no longer operate. In the case of a compressor using the sleeve valve with a yielding seat, the temperature must be limited to prevent destruction of the material forming the seat. The heated compressed air is driven from the discharge passageway past the discharge valve and into a valve chamber, and unless suitable provision is made for prevention, the heat in the walls of the valve chamber will be conducted to the cylinder head and from thence to the intake valve seat and to the cylinder walls. In prior structures the valve chamber has been formed directly on or in the cylinder head in order to bring the discharge valve seat as closely as possible to the upper end of the cylinder for minimum clearance and to insure maximum volumetric efficiency. Previous constructions have disposed the discharge valve pockets on or in the head with resultant overheating of the head by the hot compressed air. At the same time the temperature of the cylinder wall rises and unless provision is made for conducting away the heat, as by water cooling, continuous operation is impossible.

In accordance with my present invention, I place the discharge valve chamber and the discharge valve seat a considerable distance from the cylinder head and between the chamber and the head I provide means which will reduce to a minimum the conduction of heat to the head. The juncture between the valve chamber body and the cylinder head is of material which is a poor conductor of heat. A practical arrangement is to make the cylinder head and valve chamber integral and of such metal as cast iron, which has low heat conductivity, and with such arrangement I make the walls between the valve chamber and the cylinder head as thin as possible while still retaining sufficient mechanical strength. This, then, will interpose a stratum of low heat conductivity between the hot walls and valve seat of the discharge valve chamber and the cylinder head and will reduce to a minimum the conduction of heat to the bearing surfaces and the nonmetallic seat insert in the head for the intake sleeve valve.

I also provide a discharge passageway of ample volume, and in order to limit the clearance and to insure maximum discharge of compressed fluid from the cylinder, I provide an extension on the end of the compressor piston for fitting into said passageway when the piston is at the end of its compression stroke, and such extension will then act as a suction plunger in the passageway so that when the piston starts to recede, cool intake fluid will be sucked through the space between the extension sides and the passageway and into the increasing space between the extension end and the closed discharge valve, as the piston recedes, so that the walls around the discharge passageway will be cooled immediately at the beginning of the piston intake stroke and localization and accumulation of heat at the discharge end will thus be prevented. The cylinder extension engaging in the discharge passageway will also be cooled at the beginning of the recession stroke of the piston. By the foregoing arrangement I am able to secure continuous output from an air cooled compressor running at relatively high speeds and at high efficiencies, even in small sizes. While the invention is particularly applicable to compressors of small size air cooled it

is to be understood that the invention is applicable to all sizes and to water cooled compressors as well. I may employ a water hopper on the head of the compressor with the water thereof in contact with the aforementioned neck and cylinder head, but out of contact with the valve pocket.

The compressor shown in Fig. 1 of the drawing, incorporates the various features 10 of my invention;

Fig. 2 is a fragmentary view of a modified form; and

Fig. 3 is a vertical section through the head of a compressor employing a water 15 hopper.

As shown in Fig. 1 the base 1 supports the crank case structure 2 on top of which is the cylinder housing 3. The housing presents the upper and lower annular bearing surfaces 4 and 5 for the sleeve or liner 6, which 20 controls the fluid admission into the cylinder and acts also as a bearing for the piston 7, the piston being connected by the connecting rod 8 with the crank shaft 9 suitably journaled in the crank casing 2. The cylinder head 10 is secured to the cylinder body by cap screws 11. The cylinder head has the annular pocket 12 concentric with the cylinder axis in which pocket is inserted a 25 yielding seat 13, preferably of resilient material, which of necessity has relatively low heat conductivity. A substance which I have found suitable for this service is found on the market under the name of Wabco 30 and comprises a fiber base impregnated with a rubber compound. This insert forms the seat for the upper end of the liner 6, which is reciprocated by the frictional engagement therewith of the piston. The insert is held 35 in place by a threaded retaining ring. The flange 14 at the upper end of the liner surrounds the passageway 15 and forms the seating abutment for the liner. Below this flange the liner has the outwardly extending 40 flange 16 for abutting with the annular yielding stop seat insert 17 in the top of the cylinder body 3. The ring 17 is preferably made of the same material as the seat 13. Between the body 3 and the head 10 the cylinder 45 has the circumferential air intake passageway 18 protected by the annular screen 19 applied around the outer end of the passageway. When the liner 6 is in lower position, its flange 16 abuts against the seat 17 and air can then enter the cylinder through 50 the gap 20 between the liner and the seat 13, and the liner passageway 15. When the liner is raised, the gap 20 will be closed and the fluid in the cylinder will be compressed 55 during the upward movement of the piston.

The discharge valve 21 is disposed within the valve chamber 22 formed in the frame 23, the valve seating normally on the seat 24 against which it is held by the compression spring 25 abutting against the outlet

plug 26, from which extends the delivery pipe 27. In accordance with my invention, the valve chamber wall 23 and the valve seat 24 are displaced at some distance from the cylinder head, the cylinder being connected 70 with the valve chamber by the discharge passageway 15 formed in the neck 30 which, as shown, is of frusto-conical shape.

The discharge passageway 15 is of considerable volume, and in order to insure 75 complete discharge of the compressed fluid from the cylinder and from this passageway, the extension or frusto-conical dome 29 is provided on the piston 7, this extension entering the passageway 15 when the piston 80 is raised, the extension substantially filling the passageway when the piston is at the end of its compression stroke. Substantially the entire compressed fluid is thus discharged from the compression space. At the cylinder 85 head in the passageway and the upper end of the cylinder where the fluid is compressed, it will reach its highest temperature, and this heated compressed fluid is discharged into the valve chamber 22 so that the walls 90 of this chamber may become very hot, and unless stopped the heat will be rapidly conducted down to the piston head and to the seat material 13 in the head, and this material will soon deteriorate and be unable to 95 function properly. The heat also tends to be conducted from the valve pocket to the head and down to the cylinder 3 and sleeve or liner 6. Excessive temperature here will 100 cause deterioration of lubrication and result in destruction of the compressor. To prevent this, the stratum 30 between the valve chamber housing 23 and the cylinder head is of low heat conductivity. A practical arrangement comprises making the cylinder head and valve chamber housing of 105 some material, such as cast iron, which has low heat conductivity and making the stratum or wall 30 between the housing and the head in the form of a hollow neck as 110 thin as possible without losing the necessary mechanical strength. This poor heat conductive stratum resists the conduction of heat from the valve chamber housing to the metal of the head which surrounds the seat 115 insert material 13. The insert pocket 12 may be made quite large so that the cylinder head sections 31 and 32 at the top and inside, respectively, of the pocket may be comparatively thin to further decrease the conductance of heat to the seat material. The seat insert may be conveniently held in the pocket by means of a flat ring or washer 33 engaging in the peripheral notch 34 of the insert and threading along the inner wall 120 of the pocket, as clearly shown.

Attention is now called to the fact that the head 10 and cylinder frame 3 are bolted flat against each other without any intervening gasket. The cylinder frame 3 has posts or 125

brackets 39 with threaded lugs 38 at their upper ends and against these lugs the head 10 is bolted by the cap screws 11. The head and cylinder frame are, therefore, in good 5 thermal contact and any excessive temperature of the head tends to reach the cylinder frame and be thrown off by the cooling fires 40. The head may also be provided with cooling fires if desired.

10 Briefly describing the operation, while the piston is traveling downwardly, fresh fluid flows into the cylinder through the intake passageway 18 and the gap 20 between the liner 6 and the seat 13 in the cylinder head, a stream 15 of cool fluid being thus swept across the seat 13 and, in fact, across the entire bottom of the cylinder head. As soon as the piston starts to travel upwardly, the liner 6 will be moved and held by ring friction against the seat 13 20 to shut off the supply fluid and the fluid within the cylinder will be compressed and discharged past the check valve 21 into the valve chamber 22 and into the line 27. Entry of the dome 29 into the discharge passageway 28 assures substantially complete 25 discharge of compressed fluid. As described, the thin wall sections 30, 31 and 32 resist the conduction of heat from the valve chamber housing to the seat material 13. At the 30 end of the compression stroke the piston stops and reverses its motion. The rings seize the liner 6 and instantly open the gap 14, letting out immediately or venting the gas compressed into the clearance space and 35 taking it away from contact with the head, liner and piston. The dome 29, during the recession of the piston, acts as a suction plunger in the passageway 28 for, as soon as the discharge valve 21 is closed and the 40 piston starts to move downwardly and re-opens the intake gap 20, the pressure above the end of the dome in the passageway 28 will be reduced below the pressure of the incoming fresh fluid and the cool fluid will 45 thus be drawn rapidly into the space behind the dome, this cool fluid passing between the sides of the dome and the adjacent walls and extracting heat which such walls have taken on from the valve housing 23. The accumulation 50 of heat in the walls around the discharge passageway and above the seating material 13 is thus prevented. As the dome passes through the gap 20 during recession of the piston, the cool incoming fluid will 55 strike the dome sides and will reduce the temperature thereof. The heat resulting from compression is thus prevented from localizing and accumulating; the liner abutment or seat 13 is thus fully protected 60 against overheating and its life greatly increased.

In Fig. 2 I have shown an embodiment in which the valve pocket 23 is physically separated from the head 10' by a hollow block 35 of insulating material which may be mica,

lava, porcelain, or the like, clamped between the bottom of the valve pocket 23' and the top of cylinder head 10' by means of the flange 36 and bolts 37. The mode of operation and use is the same as that disclosed and 70 described in connection with Fig. 1.

In Fig. 3 I have shown a modification employing a water hopper. This water hopper is designed to cool the cylinder head shown in this modification at 41, this head 75 differing from the head 10 only in that it has an upwardly conical extending shell 42 forming a tight water hopper extending above the upper surface of the head. This hopper may be cast integral with the head 80 or it may be made as a separate sheet metal part secured to the outer periphery of the head or clamp by means of a flange under the bolt 12. Likewise, a shield or flange 43 is connected to the bottom of the frame 23 85 of the valve pocket 22 in such manner as to keep the cooling water out of contact with the walls of the pocket 22, but to permit the water in the hopper to come in free contact with the upper surface of the head 41 90 and with the neck or connection 30 through which the discharge passageway 15 is formed.

It is highly desirable to keep the water 95 out of contact with the walls of the exhaust valve pocket 22 for the reason that the water will be unnecessarily heated by the heat of the discharge compressed gas, whereas all that is desired is to cool the neck 30 and the head 41. No advantage is secured in 100 taking away the heat of the discharge valve pocket 22, so far as cooling the head is concerned. It is desirable to conduct as little heat as possible to the flange or cup 43, although I have in the illustration shown this 105 cup or flange as made integral with the bottom of the chamber 23.

It is further to be understood that instead 110 of an open hopper a closed water jacket over the head and around the neck 30 may be provided. I find, however, that with the arrangement shown in Fig. 3 continuous operation of a relatively large sized compressor may be carried on for a long time 115 with a charge of water contained in the hopper 42. The water does two things, first it gives a much greater radiating surface in conjunction with the hopper 42, and next it may, by evaporation, carry off a great amount of heat without permitting the temperature to rise above the boiling point. 120

The construction shown is not to be limited to compressors as it is adaptable to internal combustion engines and the like.

I do not intend to be limited to the details 125 shown or described.

Having described my invention, I claim as follows:—

1. In combination, a cylinder head, a 130 closed discharge valve chamber spaced from

- said head for retaining hot compressed air under pressure, a connection between said chamber and head of low heat conductivity to limit the travel of heat from said compressed air to said head, there being a passageway through said head and connection, a valve in said chamber controlling said passageway, and an intake valve having a seat supported by said head independently of 10 said passageway.
2. In combination, a cylinder head, a housing forming a valve chamber, said head and housing being cast integral of a metal of low heat conductivity, a passageway through 15 said head leading to said chamber, a valve in said chamber controlling said passageway, said housing being spaced a distance away from said head and the metal between said housing and said head being of reduced 20 cross sectional area in order to retard the conduction of heat therethrough and a relatively stationary intake valve below the head.
3. In combination, a cylinder having a cylinder head, a housing forming a valve chamber, a passageway from said cylinder to said chamber, a valve in said chamber controlling said passageway, said housing being spaced from said head, and a wall connecting 30 said housing and head, said wall being of poor heat conductive material and of reduced cross section in order to retard conduction of heat therethrough and a separate intake passageway under the head and a relatively 35 stationary valve therefor.
4. In combination, a cylinder having a fluid inlet, an imperforate piston reciprocable in said cylinder, a head for said cylinder, a housing forming a valve chamber connected with said head, said housing being displaced a distance away from said head, a discharge passageway through said head and housing, a discharge valve in said chamber, and an extension on said piston for engaging 40 in said passageway during discharge stroke of the piston.
5. In combination, a cylinder having a fluid inlet, a piston in said cylinder, a head for said cylinder, a relatively stationary inlet valve below the head, a housing forming a valve chamber co-axial with said cylinder, said housing being spaced a distance away from said head and supported thereon, an extended passageway through said head and 50 housing for connecting said cylinder with said chamber, a discharge valve seated in said chamber, and a plunger extension on said piston for engaging in said passageway during the discharge stroke of the piston 55 for expelling the fluid from said passageway into said chamber.
6. In a compressor, the combination of a cylinder having a fluid inlet, a piston for said cylinder, a housing forming a valve 60 chamber, walls forming a passageway be- 70 tween said cylinder and chamber and supporting said housing on said head, said walls being of comparatively small cross sectional area whereby to resist conduction of heat therethrough, a discharge valve in said chamber controlling said passageway, said passageway being out of thermal contact with the fluid drawn through the fluid inlet, and a plunger extension on said piston for fitting into said passageway to discharge the compressed fluid therefrom during the compression stroke of the piston.
7. In combination, a cylinder having a head, a frame forming a valve chamber, an elongated neck supporting said frame on said head, a passageway through said head and neck into said valve chamber, a valve in said valve chamber controlling said passageway, said neck being of material 80 resistant to heat conduction, said cylinder having a separate intake passageway out of thermal contact with the discharge passageway.
8. In combination, a cylinder, a structure forming a head for said cylinder and a valve chamber, a passageway through said structure connecting said cylinder and chamber, a valve in said chamber controlling said passageway, the structure between said chamber and head being contracted to provide insulating space between said chamber and head and an elongated neck of reduced cross sectional area for resisting the conduction of heat between said chamber and head, said cylinder having a separate intake passageway out of thermal contact with the discharge passageway.
9. In combination, a cylinder having a movable liner, a head for the cylinder, a seat of yieldable material supported on the inner side of said head in position to be engaged by the upper end of said liner during upstroke of the piston, a housing above said head forming a valve chamber, a passageway through said head and housing to said chamber, a valve in said chamber controlling said passageway, the material between said seat material and said chamber being of reduced cross section for resisting the conduction of heat from said chamber to said material.
10. In a compressor, the combination of a cylinder, a movable liner therefor, a head for the cylinder, a seat of yielding material supported on the inner side of said head to be engaged by said liner during compression stroke of said piston, a housing forming a valve chamber, a passageway connected to said cylinder and chamber, a valve in said chamber controlling said passageway, said housing being displaced from said head by an extended air space and the material between said housing and said seat material being of a nature to resist the conduction of heat from said chamber to said material.

11. In a pressure fluid device, a cylinder having a head, a gas discharge passage leading through the head, a valve for said passage, and a neck of relatively low heat conductivity separating said valve from said head and defining said passage, said cylinder having a separate intake passageway out of thermal contact with said discharge passageway.
12. In a pressure fluid device, a cylinder having a head, a gas discharge passage leading through the head, a valve for said passage, a neck of relatively low heat conductivity separating said valve from said head and defining said passage, and a water jacket for said head and neck out of thermal contact with the compressed gas beyond the valve.
13. In combination, a cylinder head, a discharge valve chamber spaced from said head, a connection between said chamber and head of low heat conductivity, there being a passageway through said head and connection, a valve in said chamber controlling said passageway, and cooling means for cooling said head and connection, said means being out of thermal contact with the discharge valve chamber.
14. In combination, a compressor having a cylinder, a head for the cylinder, a discharge valve chamber mounted on said head but separated therefrom by a neck of low heat conductivity, a discharge passageway extending through the neck and to said discharge valve chamber, a discharge valve controlling said passageway, and an inlet valve disposed below the head, said valve having a seat on said head.
15. In combination, a compressor, a cylinder therefor, a head for the cylinder, a discharge valve chamber mounted on said head but separated therefrom by a neck of low heat conductivity, a valve in said chamber, and an annular inlet valve disposed below the head at the upper end of the cylinder and providing a narrow opening of relatively great length into the upper end of the cylinder.
16. In an air compressor having a cylinder and a piston, the method of limiting the temperature rise of the cylinder head which comprises compressing a charge of air in the cylinder, discharging said air from the cylinder to a closed chamber substantially free of thermal contact with the cylinder and 55 cylinder head, closing off the chamber from the cylinder head at the end of the discharge stroke to hold the hot compressed air away from the cylinder head, and drawing a charge of air into the cylinder through a 60 path which is substantially free of thermal contact with the air under compression.
17. In a compressor, a cylinder having a head, a discharge valve chamber spaced from the head and adapted to retain air under 65 pressure, a piston for said cylinder, crank means for reciprocating said piston in said cylinder, said piston and cylinder having a relatively small clearance to provide a relatively high compression ratio, said chamber 70 having a discharge check valve and being connected to the cylinder by a hollow connection of low heat conductivity, and an air intake passageway independent of said discharge connection.
18. In a power driven compressor of the type adapted for continuous compression of a gas and in which heating of the head becomes a limiting factor, the combination of a cylinder and piston, a head for the cylinder, a discharge valve chamber spaced from the head and communicating with a closed reservoir, a valve for said chamber, a hollow connection of low heat conductivity leading from the cylinder to said chamber, said 80 compressor having an intake passageway out of heat conducting relation with the discharge passageway.
19. In combination, a cylinder head, a discharge valve chamber spaced from said head 90 and adapted to retain heated gases under pressure, a connection between said chamber and head of low heat conductivity, there being a passageway through said head and connection, a valve in said chamber controlling said passageway, and a yielding intake valve seat mounted on the bottom of the head.

In witness whereof, I hereunto subscribe my name this 31st day of August, 1925.

BURTON S. AIKMAN.
